(57) **CLAIM**

The ornamental design for a tool case, as shown and described.

DESCRIPTION

FIG. 1 is a perspective view of a tool case showing the present invention;

FIG. 2 is a left elevational view thereof;

FIG. 3 is a right elevational view thereof;

FIG. 4 is a top plan view thereof;

FIG. 5 is a bottom plan view thereof;

FIG. 6 is a rear elevational view thereof; and,

FIG. 7 is a front elevational view thereof.

The broken lines showing portions of tool case are for the purposes of illustrating environment and forms no part of the claimed design.
